UNITED STATES PATENT OFFICE.

EDWARD P. BEACH, OF NEWARK, NEW JERSEY.

DESIGN FOR A FINGER-RING.

SPECIFICATION forming part of Design No. 20,735, dated May 19, 1891.

Application filed April 7, 1891. Serial No. 388,025. Term of patent 3½ years.

To all whom it may concern:

Be it known that I, EDWARD P. BEACH, a citizen of the United States, residing at Newark, in the county of Essex and State of New Jersey, have invented and produced a new and original Design for Finger-Rings; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Referring to said drawings, in which similar letters of reference indicate corresponding parts in each of the several figures where they occur, Figure 1 represents a plan, and Fig. 2 a side elevation, of a finger-ring, showing my design. Fig. 3 represents in plan a modification of the same, these views being deemed sufficient to fully illustrate the design.

The leading feature of my design consists more particularly in the peculiar configuration of the seal portion of the ring, which presents the appearance of two strands or wires twisted and intertwined with one another and forming a single knot *a*, the body *b* of the ring presenting the appearance of a series of strands or wires lying laterally adjacent to one another and intersecting with said knot at each side, as clearly indicated in the drawings. In Fig. 3 is shown a double knot of the same design.

What I claim is—

The design for a finger-ring herein shown and described.

In testimony that I claim the foregoing I have hereunto set my hand this 2d day of April, 1891.

EDWARD P. BEACH.
